SCARF

Lester K. Thorman, Woodmere, N. Y., assignor to
 Benjamin Wolf Co. Inc., New York, N. Y., a corporation of New York

Application January 8, 1938, Serial No. 183,948

3 Claims. (Cl. 2—207)

This invention relates to scarfs; more particularly to convertible handkerchief scarfs. Handkerchief scarfs as known to me comprising, generally, a square of fabric which may be designated as a handkerchief or bandanna, have been popularly employed as scarfs. The square section is usually folded over diagonally and the diagonal ends tied about the neck. Also, the scarf has been draped about the head, using the diagonal ends as ties beneath the chin, to give a more or less peasant type of headdress.

The draping of a scarf of this character requires skill and, further, the draped fabric is not securely in position, particularly where the fabric is of silk, which makes a knot insecure.

It is an object of my invention to provide a scarf construction which may be quickly and facilely draped in a variety of positions so that it may be worn as a neck scarf, or as a headdress and so applied in position with little or no skill on the part of the wearer.

It is a further object of my invention to provide a scarf of the handkerchief type, which is quickly and facilely convertible to be worn as a neck scarf or headdress, each of which positions may be retained by the wearer with security and ease of operation, and to provide a highly desirable ornamental article of apparel.

To attain these objects and such further objects as may appear herein or hereinafter be pointed out, I make reference to the accompanying drawing forming a part hereof, in which

Figure 1 is a perspective view of my device; Figure 2 is a perspective view to show the position thereof, preparatory to positioning the same over the wearer;

Figure 3 is a perspective view of my device draped upon the head of a wearer, in one convertible position thereof;

Figure 4 is a perspective view of another convertible form of my device, when worn as a neck scarf;

Figure 5 is a perspective view showing a still further convertible form of my device; Figure 6 is a back view of the same.

Making reference to the drawing, it is contemplated by me to provide a scarf 10, preferably made from a square section of fabric, suitably finished at the edges thereof in the well known way. This square of fabric, for the provision of my device, is folded along the diagonal line 11, to provide sections 12 and 13 of triangular configuration, with the edges 14 and 15 contiguous and in alignment at one side of the triangular section and the edges 16 and 17 overlying each

other and contiguous at another side of the triangular sections and the corners 17 and 18 overlapping each other, leaving corners 19 and 20 at the opposite ends.

In this position, fastening means 21, in the form of slide fasteners, are provided, affixing the complementary sections 22 and 23 along the edges 16 and 17, respectively, for a predetermined length and leaving an opening 24, without any connecting means. It is preferred that the fastening means be of the character which permanently joins the corners 17 and 18 together by the anchoring means 25, usually associated with slide fasteners of the character mentioned. Associated with the complementary sections 22 and 23 of the slide fasteners, there is the usual operating member 26.

With a construction as provided, it will be apparent that with the complementary sections 22 and 23 of the slide fasteners brought together, as shown in Figure 1, a limited orifice 24 will be provided and an extended orifice 27 will be left, as formed by the edges 14 and 15.

With the operating member 26 slid to the position adjacent the corners 17 and 18, the scarf may be slipped over the head of the wearer, the head first passing through the opening 26 and emerging through the opening 34. The scarf may then be adjusted to permit the corners 19 and 20 to fall over the back of the wearer, with the corners 19 and 20 more or less overlying each other. This general position will be assumed, as will be more clearly apparent from an inspection of Figure 4.

Should it be desired to obtain a closer binding of the edges 16 and 17 towards each other, to obtain a snugger draping of the scarf around the neck, the slide fastener operating member 26 may be slid upwardly, to achieve the position shown more clearly in Figure 4, in dotted lines.

Where it may be desirable to provide a scarf which is draped over the head H, in peasant fashion as already referred to and as illustrated in Figure 3, the corner 20 is drawn over the top of the head, leaving the edges 14 and 15 to surround the neck and shoulders. The face will then protrude through the opening 24. A close adjustment may be obtained by connecting the edges 16 and 17 by upwardly sliding the operating member 26, joining the slide fastener sections 22 and 23 to each other. Suitable locking means (not shown) may be included by the operating member 26, to prevent retraction of the operating member in a manner well understood and known to be associated with this type of device.

In this manner it will be observed that a secure closure is provided beneath the chin of the wearer, leaving the corner 28 to be draped in any desired way. The sections 12 and 13 then may be draped over the chest and shoulders, to give adequate protection, as well as the ornamental effect of the scarf fabric.

Where it is desired to use the scarf as an ordinary, well known type of tie from the triangular, 10 double-folded section shown in Figure 1, the corners 19 and 20 may be tied beneath the chin in the manner shown in Figure 5, leaving the corners 17 and 18 to fall over the back of the wearer. The inclusion of the fastening means 21 15 does not interfere with the employment of the scarf in the usual way, as illustrated in Figure 5, and the weighting obtained from the fastening means enhances the adjustment of the device for this purpose.

20 It will thus be observed that I have provided a convertible scarf which has the desirable objects heretofore emphasized, facilitating the adjustment of this type of garment in position, while securely holding the same in any of the desired 25 positions.

It will also be observed that while I have described and illustrated the slide fastener means as those preferred by me in that a wide degree of 30 variability may be obtained, other fastening means may be employed, though not as convenient or adaptable for my purposes.

It will also be observed that while I have described and illustrated a type of slide fastener means for connecting predetermined lengths of 35 the edges 16 and 17 to each other, and securely anchoring the corners 17 and 18 by the anchor member 28, separable fastening means for these corners may be provided.

In general, it will be observed that by the connection of the edges 16 and 17 to each other by. 40 fastening means, particularly the fastening means herein preferably contemplated by me, I not only achieve convertibility but the portions of the garment of the character described which 45 are usually tied together may be flattened out over the chest and neck of the wearer, permitting the most extended use of the fabric of the scarf in that the material necessary for making of the knot is not expended. Thus, sections of fabric 50 which normally would not be enough to be draped over the head may thus be utilized for this purpose.

It will also be observed that while I have shown in the preferred form of my invention, the employment of a square section of fabric, any configuration which, upon folding, will bring together 55 two contiguous sections to give an entrance opening and an exit opening for the neck and face, respectively, may be employed and for illustration purposes, the section of the fabric may be one defined along the line x-x, wherein a substantially triangular section of fabric may be employed.

While I have described and illustrated as the 60 preferred form of my invention, a scarf made

from a square section of fabric, it will be understood that my invention is not limited to such sections of fabric but that my invention is to be determined by the scope of the appended claims.

Having thus described my invention and illustrated its use, what I claim as new and desire to secure by Letters Patent is—

1. A scarf of the character described comprising a square section of fabric, a pair of diagonally opposed corners whereof are joined and along 10 a pair of the edges whereof, directed from said corners to an intermediate corner, there are attached for a predetermined length of said edges, separable fastening means comprising complementary interlocking connector elements affixed 15 to said edges and arranged to join the obverse surface of the fabric to dispose the same substantially continuously at the portions joined, a slider operating member for said elements whereby contiguous edges so brought together leave an 20 opening between the corners joined and the intermediate corner of the fabric, the position of the slider operating member in relation to the interlocking connecting elements determining the size of the opening, to attain variability of the size of 25 the opening, the construction thereby providing a plurality of openings, cooperating with the fastening means so provided to permit the fabric to be variously draped and held in the draped positions upon the wearer.

2. A handkerchief scarf comprising a substantially square section of fabric, with a pair of its diagonally opposed corners joined to each other, providing superimposed, substantially triangular sections, and adjustable fastening means extending 35 from the corners so joined and along the edges thereof in a direction towards a contiguous corner of the fabric, providing an opening of adjustable dimensions for the contiguous edges so joined for a distance between the diagonally 40 joined corners and the contiguous corner, the construction thereby providing a plurality of openings, cooperating with the fastening means so provided to permit the fabric to be variously draped and held in the draped positions upon the 45 wearer.

3. A handkerchief scarf comprising a substantially square section of fabric with a pair of its diagonally opposed corners brought together, leaving the contiguous corners free, and having 50 along the edges of the fabric from the corners so joined, and attached thereto, complementary interlocking connector elements, a slide operating member for said elements, the interlocking elements and operating member providing an opening of adjustable dimensions between the diagonally joined corners and a contiguous corner, said operating member including locking means to prevent accidental displacement of the operating member, the construction thereby providing a plurality of openings cooperating with the fastening means so provided to permit the fabric to be variously draped and held in the draped positions upon the wearer.
